INVENTOR.

UNITED STATES PATENT OFFICE.

FREDERICK W. KOONZ, OF GREENFIELD, MASSACHUSETTS, ASSIGNOR TO ROGERS, LUNT & BOWLEN COMPANY, OF GREENFIELD, MASSACHUSETTS, A CORPORATION OF MASSACHUSETTS.

DESIGN FOR A HANDLE FOR A SPOON, FORK, OR SIMILAR ARTICLE.

58,492.

Specification for Design.

Patented July 26, 1921.

Application filed February 8, 1921. Serial No. 443,480. Term of patent 14 years.

To all whom it may concern:

Be it known that I, FREDERICK W. KOONZ, a citizen of the United States, residing at Greenfield, in the county of Franklin and State of Massachusetts, have invented a new, original, and ornamental Design for a Handle for a Spoon, Fork, or Similar Article, of which the following is a specification, reference being had to the accompanying drawing, forming a part thereof.

Figure 1 is a front plan view of a handle for a spoon, fork, or similar article showing my new design.

Fig. 2 is a rear plan view thereof.

Fig. 3 is a sectional view on the line 3—3 as indicated.

I claim:

The ornamental design for a handle for a spoon, fork, or similar article as shown.

In testimony whereof I affix my signature in presence of two witnesses.

FREDERICK W. KOONZ.
